UNITED STATES PATENT OFFICE.

EDNA SIBLEY TIPTON, OF JACKSON HEIGHTS, NEW YORK.

PERFUME CONTAINER AND DISPENSER.

Application filed February 26, 1926. Serial No. 90,990.

This invention relates to a toilet article in the form of a small compact container and dispenser for perfume, and which is adapted to be carried in a lady's hand-bag, or in the pocket, and inasmuch as, in general appearance and in its operation, this device resembles a fountain pen, I contemplate as a commercial name for this article, the term "perfume pen".

10 The construction, operation and use of my improved container and dispenser are set forth in the following specification with sufficient clearness to enable others skilled in the art to which its construction relates, to make 15 and use the same, reference being had to the accompanying drawings in which:

Fig. 1 is a side elevation of my improved container.

Fig. 2 is a central, longitudinal section of 20 the barrel of the container showing the combined feed and vent valve or plunger in the closed position.

Fig. 3 is a central, longitudinal section of 25 the barrel of the container showing the combined feed and vent valve in the open position, as in dispensing the perfume.

Fig. 4 is an upper end, or plan view, of the 30 container with the plunger or valve taken in section on line 4—4 of Fig. 3.

Fig. 5 is a view showing the operation of 35 filling the barrel of the container from a bottle of perfume.

In Figs. 1, 2 and 3, the device is shown considerably enlarged for the sake of clear illustration, and the size shown in Fig. 5 is about 40 the size usually employed for my device when made of thin material, such as gold, silver, celluloid, etc.

The construction illustrated in the drawings is substantially as follows:

A barrel, 1, is provided, which, at its lower end is preferably tapered, as indicated at 2. The upper end of said barrel 1 is provided with a removable closure element or cap 3 which is centrally pierced for the reception of a longitudinally-movable plunger 4, which also passes through the lower feed end of said barrel. Said plunger 4 is adapted to serve the purposes of a feed and a vent valve in the following manner: The lower end of said plunger, is tapered at the portion 5, and for the seating of said tapered end, a correspondingly-tapered aperture or seat 6 is provided in the lower, feed end of said barrel whereby 55 a leak-tight closure is provided for said aper-

ture 6, when said plunger is in the position shown in Figs. 1 and 2 of the drawings. The upper end of said plunger is flattened at two opposite sides, as indicated at 7, said flattening being accomplished by removing or cutting away a portion of the periphery of the plunger. Said flattened portions serve as and are utilized for the purpose of a vent for the ingress of air into said barrel when said plunger 4 is in the position shown in Fig. 3, 60 as in the release or dispensing of perfume from the container.

Said plunger, adjacent its upper end is provided with a rigidly-attached collar 8, between which and the adjacent, lower face of the cap 3, is interposed a compression spring 9 which is arranged and normally acts to yieldably retain said plunger 4 in its feed and vent closing position, as shown in Fig. 2, and also serves to automatically return said 70 plunger to said position after being manually actuated out of said closed position, for the release of perfume from the container.

When the container is to be filled with perfume, its feed end is inserted into a bottle containing perfume, as shown in Fig. 5 with the plunger point 5 resting upon the bottom of the bottle and sufficient downward pressure is exerted upon said barrel to actuate said plunger 4 into its open position, and, if the bottle contains a sufficient amount of perfume, it will flow by gravity into and fill the barrel 1. If, however, there is not sufficient perfume in the bottle, a suction device, preferably in the form of a rubber bulb 10 may be 80 temporarily attached to the upper end of said barrel,—being properly compressed before such attachment,—and when the reaction or expansion of said bulb takes place fluid is drawn into, and fills said barrel. When 85 the point of the plunger is raised from contact with the bottom of the bottle, the expansion of the spring 9 will cause the portion 5 of said plunger to seat, leak-tight, within its seat 6, and at this juncture the upper end of 90 said plunger also forms a leak-tight closure for its carrying aperture in the cap 3, as shown in Fig. 2.

Perfume may be dispensed from my improved container and dispenser, as desired, 105 by placing the feed end of the plunger in contact with the article to be scented or perfumed and exerting sufficient pressure thereon to actuate said plunger into its open and venting position, as indicated in Fig. 3, 110

whereupon perfume will be released from the feed end of the barrel 1.

The feed end of said barrel may be supplied with a removable cap, if this is found to be desirable, for the purpose of preventing the accidental actuation of said plunger into its fluid-releasing position.

I claim the following:

1. A perfume container and dispenser comprising a cylindrical barrel arranged to contain perfume, a feed aperture for said barrel, a vent aperture for said barrel, and an element normally closing said apertures, said element being formed and adapted to be actuated at will into a position wherein and whereby said apertures are simultaneously opened, for the purposes set forth; the wall of said barrel surrounding said vent aperture being adapted for the application of a suction device thereto to fill the barrel.

2. A perfume container and dispenser comprising a cylindrical barrel adapted to contain perfume, a feed aperture at one end of said barrel, a vent aperture at the other end of said barrel, and a longitudinally-movable plunger extending through said apertures and adapted and normally positioned so as to close the same, said plunger being actuatable at will to a position wherein and whereby said apertures are simultaneously opened for the purposes set forth; the feed aperture end of said barrel being arranged and adapted to be inserted into the mouth of a perfume bottle and into the liquid contained therein with the adjacent end of said plunger resting upon the bottom of the bottle whereby said plunger is actuated into its open position, thus allowing liquid to flow into said barrel by gravity.

the bottom of the bottle whereby said plunger is actuated into its open position, thus allowing liquid to flow into said barrel by gravity.

3. A perfume container and dispenser comprising a cylindrical barrel adapted to contain perfume, a tapered feed aperture at one end of said barrel the taper of which converges outwardly, a vent aperture in the other end of said barrel, a longitudinally-movable plunger having its ends respectively positioned within said apertures with each end normally closing its respective aperture, said plunger being formed, arranged and adapted to simultaneously open said apertures when the feed end of said plunger is actuated inwardly, and means adapted to automatically actuate said plunger into its aperture-closing position and yieldably retain same therein; the feed aperture end of said barrel being arranged and adapted to be inserted into the mouth of a perfume bottle and into the liquid contained therein with the adjacent end of said plunger resting upon the bottom of the bottle whereby said plunger is actuated into its open position, thus allowing liquid to flow into said barrel by gravity.

4. The construction set forth in claim 2 characterized by the adaptation that when said apertures are opened said barrel may be filled by applying suction to its vent end.

In testimony whereof I affix my signature.

EDNA SIBLEY TIPTON.
